(No Model.)

D. NEILLY.
SEWING MACHINE.

No. 257,052.

Patented Apr. 25, 1882.

UNITED STATES PATENT OFFICE.

DANIEL NEILLY, OF BRADFORD, ASSIGNOR TO HIMSELF AND JAMES BLAIN,
OF GILFORD, ONTARIO, CANADA.

SEWING-MACHINE.

SPECIFICATION forming part of Letters Patent No. 257,052, dated April 25, 1882.

Application filed January 17, 1882. (No model.)

To all whom it may concern:

Be it known that I, DANIEL NEILLY, of Bradford, in the Province of Ontario, Canada, have invented a new and useful Improvement 5 in Sewing-Machines, of which the following is a full, clear, and exact description.

The object of my invention is to facilitate the work of sewing with machines; and it consists in certain devices by which the presser-bar can be moved and the thread slackened by the same hand at the time of stopping or starting the machine; and, further, in tension devices, all as hereinafter described and claimed.

Reference is to be had to the accompanying 15 drawings, forming part of this specification, in which similar letters of reference indicate corresponding parts in all the figures.

Figure 1 is a side view of a sewing-machine fitted with my improvements. Fig. 2 is a top 20 view of the same, partially in section. Figs. 3 and 4 are detail cross-sections on the lines *x x* and *y y* of Fig. 2.

A is the bed; *B*, the arm. *C* is the balance-wheel; *D*, the presser-bar, and *E* the needle-bar, of ordinary construction and arrangement.

F is a rod or bar extending lengthwise and at one side of arm *B*, and sustained thereon in bearings *a a*.

b is an arm fixed on one end of rod *F*, beneath a lifting-lug, *c*, that projects from presser-bar *D*, (see Fig. 4,) the other end of rod *F* being bent to form a handle portion, *d*, next to the balance-wheel *C*.

e is a weighted arm fixed on the rod, so that it tends to turn the same in a direction to release arm *b* from the lug *c*, said arm *e* being formed with a projection, *e'*, (see Fig. 3,) by which the movement is limited.

It will be seen that the presser-bar can be raised by bringing down the end *d* of rod *F*, and when fully raised a notch in lug *c* is engaged by the end of arm *b*, and the parts thus retained. The thread-slacking device is at the 45 other side of arm *B*. *G* is a bent lever, pivoted at *f*, and having on its outer end an eye, *g*, through which the thread will pass from the tension devices.

h is a slide attached on arm *B* by a screw, *t*, 50 passing through a slot in the slide. The slide

h is connected to lever *G*, so that the lever can be raised by moving the slide, and its other end contiguous to wheel *C* is bent up to form a finger-piece. This arrangement brings the balance-wheel, the handle of the rod *F*, and 55 the finger-piece of the thread-slackener all together, where they can be operated by one hand of the operator. To illustrate, the presser-foot being raised and the goods placed for sewing, the right hand of the operator is to be 60 placed on the wheel to start the machine, as usual, and by the same motion the thumb is placed beneath the end *d* of rod *F* to raise said end and release the presser-bar. In turning a corner, while the hand is placed on the wheel 65 to slacken the speed, the thumb can be readily placed on rod *F* and the presser-foot raised sufficiently to allow the goods to turn. When the goods are to be removed the presser-bar is raised by pressing the end *d* of rod *F* downward, and at the same time the thumb is placed 70 on the bent end of slide *h* and the slide moved, and the lever *G* being thereby raised, the thread is drawn from the spool to the extent required for slackening. In all these movements but 75 one hand is used, leaving the other free to handle the goods, and the operations can be done almost entirely by feeling. Time is thus saved, and the sewing carried on with great convenience and facility.

The tension devices consist of a plate, *i*, bent in **U** form and fixed on arm *B*, and two spring-tongues, *k l*, attached at their mid-length by a screw, *m*, entering one end of the plate. The thread passes through a slot, *k'*, 85 in the upper tongue and between the outer ends of the two tongues, these ends being pressed together by a set-screw, *n*, tapped through the plate *i*. The slot *k'* is partially covered by a spring-plate, *o*, held down by 90 screw *m*, so that it retains the thread in the slot. To place the thread it is passed beneath the end of spring *o* until it is within the slot *k'*, and it is then drawn between the tongues, this being done without letting go of the thread. 95

It is also to be observed that the ends of the tongues *k l* where the thread is held are unsupported, and may thus move with the thread up and down without slackening the tension.

Having thus fully described my invention, I 100

claim as new and desire to secure by Letters Patent—

1. In a sewing-machine, the combination, with the arm B, the presser-bar D, provided

5 with the lug e, and the rod F, journaled in bearings on the side of the said arm, and provided with the arm b and the handle d, of the weighted arm e, having projection e', substantially as and for the purpose set forth.

10 2. In sewing-machines, the lever G, provided with eye g, and the slide h, in combination with the arm of the machine, substantially as and for the purposes set forth.

3. The combination, in a sewing-machine, of the presser-bar raiser F and thread-slackener 15 G, fitted for being operated contiguously to the balance-wheel, substantially as shown and described.

4. The tension device consisting of spring-tongues k l, provided with a slot, k', the U-shaped plate i, and the spring o, combined for use as shown and described.

DANIEL NEILLY.
